UNITED STATES PATENT OFFICE.

DE LANCY FREEBORN AND RICHARD B. PERKINS, OF HORNELLSVILLE, N. Y.

METALLIC CORNER FOR BOXES.

SPECIFICATION forming part of Letters Patent No. 254,436, dated February 28, 1882.

Application filed December 13, 1881. (No model.)

To all whom it may concern:

Be it known that we, DE LANCY FREEBORN and RICHARD BOONE PERKINS, of Hornellsville, in the county of Steuben and State of New York, have invented certain new and useful Improvements in Metallic Corners; and we do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of our improved box or body corner-piece. Fig. 2 is a similar view from the outside. Fig. 3 is a section taken on the line *x y z* of Fig. 2, and Fig. 4 is a section taken on the line *m n* of the same figure.

20 This invention has relation to improvements in box or body corner-pieces, its object being to effect the ready and substantial fastening together of the sides, ends, and bottom of the body or box, and to permit of the ready renewal of any one or more of the parts, as well as to protect the corners or angles; and it consists in the combination and arrangement of parts, substantially as hereinafter more fully set forth and claimed.

30 In carrying out our invention we employ an outside plate, *A*, and an inside plate, *A'*, adapted one to fit against the outside of the corner and the other against the inside of the corner of the box or body, and both connected 35 together by a web or third plate, *A²*. The plates *A* *A'* are connected together at the upper end by a top plate, *A³*, while the plate *A'* is provided at its lower end with an inwardly-projecting plate or flange, *A⁴*, through which 40 bolts or screws or similar means are inserted;

fastening the corner-piece to the bottom frame of the body or box, as particularly seen in Fig. 1.

The corner-piece, as constituted of the parts *A* *A'* *A²* *A³* *A⁴*, may be cast in one piece, in 45 which case it is applied for use by slipping it on the parts of the box or body vertically, its open bottom side being presented toward the upper edge of the box or body, or by driving or inserting the sides and ends into it endwise 50 and then bolting or screwing it thereto.

From the foregoing it will be observed that the ends of the sides and the end portions of the box or body previously beveled will abut against the web *A²*, while the latter will thus 55 be permitted to re-enforce or strengthen the corner-piece and hold both the plates of the corner-piece and the parts of the box or body firmly together.

The edges of the outside plate, *A*, are provided with beads *a* to protect or overlap the edges of the parts of the box or body where, if desired, the plate is let into the same.

Having thus fully described our invention, we claim and desire to secure by Letters Patent—

The corner-piece consisting of the outside and inside plates, *A* *A'*, having, one, beads *a*, the web *A²*, connecting these together, the top plate, *A³*, and the base-plate *A⁴*, all cast in 70 one piece, as set forth and shown.

In testimony that we claim the foregoing as our own we have hereunto affixed our signatures in presence of two witnesses.

DE LANCY FREEBORN.
RICHARD BOONE PERKINS.
